Term of patent 14 years

Int. Cl. D6—01; D20—03

U.S. Cl. D26—14

FIG. 1 is a front perspective view of a combined telephone message holder and advertising display card or similar article, embodying my new design.

FIG. 2 is a reduced top plan view thereof.

FIG. 3 is a reduced rear elevational view thereof.

FIG. 4 is a reduced bottom plan view thereof.

FIG. 5 is a reduced front elevational view thereof.

FIG. 6 is a reduced right side elevational view thereof.

FIG. 7 is a further reduced left side elevational view thereof.

The dominant features of my design reside in the portions shown in full lines, the broken line representation of the telephone in FIG. 7 is shown for illustrative purposes only.

I claim:

The ornamental design for a combined telephone message holder and advertising display card or similar article, substantially as shown and described.
